SAND BLASTING APPARATUS

Horace B. Fay, Shaker Heights, and Nelson J. Quinn, Toledo, Ohio

Application March 4, 1935, Serial No. 9,884

16 Claims. (Cl. 51-9)

The present invention, relating as indicated to sand blasting apparatus, is more particularly directed to a new and improved apparatus for projecting sand, shot and the like at a high speed against various surfaces for the purpose of cleaning, roughening or otherwise preparing the surface. The principal object of the present invention is the provision of an apparatus for the purposes referred to which shall be simple 5 in construction, sufficiently light in weight to be readily portable and much lower in operating cost than the air-operated sand blasting apparatus which is now in general use.

To the accomplishment of the foregoing and related ends, said invention, then, consists of the steps hereinafter fully described and particularly pointed out in the claims; the annexed drawings and the following description setting forth in detail certain structure embodying the invention, such disclosed means constituting, however, but one of various mechanical forms in which the principle of the invention may be used.

In said annexed drawings:

- 25 Fig. 1 is a side elevation of our improved apparatus; Fig. 2 is a section on the line 2—2 in Fig. 1; Fig. 3 is a plan view more or less diagrammatic in character of a modification of the apparatus of Figs. 1 and 2; Fig. 3 is a plan view 30 of a modified type of wheel for use in our apparatus; Fig. 4 is a partial sectional view of a modification of the wheel; Fig. 5 is a partial edge view of the wheel of Fig. 4; Fig. 6 is a partial side elevation of another modification of the 35 wheels; Fig. 7 is a view partially diagrammatic showing another means for adjusting the axial spacing between the rolls; Fig. 8 is a side elevation partially in section showing another method of feeding abrasive to the rolls; Fig. 9 is a fragmentary side elevation showing means for feeding 40 the abrasive and the relationship between the rolls; Fig. 10 is a plan view of the rolls showing in section the abrasive discharge nozzle; and Fig. 11 is a side elevation partially in section of 45 a modified wheel.

Sand blasting is an operation usually carried out by feeding abrasive, such as finely divided sand, shot or the like into a stream of compressed air and then directing the stream of air 50 and abrasive through a restricted nozzle onto the surface to be treated. This method of cleaning is extremely effective, particularly in the roughening and thorough cleaning of surfaces of metal to which other metals are to be bonded, 55 the removal of pitted rust and scale and the

cleaning of rough or irregular surfaces, such as stone or the like, but it has several serious objections, of which the foremost is probably the cost of the operation. Air at high pressure has to be used and the compressing and storing of 5 air represents a very considerable expense, while large volumes of air have to be used in any continued sand blasting operation. The upkeep of equipment is very considerable as the sand is carried at high speed and cuts away the restricted nozzles, which have to be replaced at frequent intervals. A further objection is the volume of air which has to be handled after it leaves the nozzles and the scattering effect of 10 this very large volume of air upon the abrasive. 15 as it carries the abrasive not only to the work but away from it, scattering it in all directions and making it advisable to operate in a closed room where the abrasive can be collected for salvage. If this is not done, the abrasive is 20 wasted and the cost of the operation is thereby additionally increased. In manufacturing operations where metal finishing is conducted after the cleaning or sand blasting operation, sand blasting is particularly objectionable as it fills 25 the air for long distances from the place of sand blasting with minute particles of abrasive which are detrimental to all types of machinery with which they come in contact.

The present apparatus is designed to provide 30 the same effect as air sand blasting without the objectionable effects of scattering of the abrasive of high upkeep and operating cost.

We have found that by supplying finely divided abrasive, such as sand or shot, between two 35 rapidly moving members which are substantially in contact and which are provided with yieldable surface elements, that the material is passed through the moving elements, discharged in substantially a single flat plane and given 40 a speed which is as high or which may be higher than the speeds imparted to sand by air even under pressure up to 100 pounds. In addition to these advantages the present apparatus is adapted to handle larger volumes of abrasive 45 with a resulting increase in the abrading action on the surface treated than is possible with air-operated apparatus.

Referring now to Figs. 1 and 2, we have shown a casing 1, in which are mounted two movable 50 elements in the form of rotatable wheels 2 and 3, provided with yieldable surface coatings in the form of elastic bands 4, which are preferably of relatively soft rubber molded or bonded to the outer surface 5 of the wheels. The casing 55

is provided with handles 6 and 7 for convenient manipulation by an operator and has the wheels disposed in parallelism and so mounted that they contact at the central plane 8. Abrasive is applied to the wheels through an inlet conduit 9 mounted in the upper side of the casing 1 and terminating closely adjacent to the entering throat openings 10 between the two rotatable members.

Either one or both of the two rotatable members may be driven, but we have found it unnecessary to drive both since the rotation of either wheel at high speed slightly distends the elastic band 4 and this increase in the diameter of the band causes it to contact the band on the adjacent wheel even if the two wheels are not already in contact. In this way one wheel drives the other at the same speed and we have found that a speed of between 9000 and 15000 surface feet a minute gives a very effective cleaning action, although it will be apparent that the speed of rotation of the wheel may be varied, depending upon the material employed and the nature of the work.

Any suitable means may be used for driving the rotatable members, but in Fig. 9 we have shown the end of a flexible shaft 11 which is removably secured to a housing 12 attached to the casing, and the flexible shaft may of course be operated from any suitable source of power. Very little power is required to operate the apparatus after the wheels have been brought up to speed and the power consumption compared to that of any air-operated apparatus is almost negligible in terms of cost.

The wheels 2 and 3 are shown in Fig. 2 as mounted upon shafts 13 and 14 respectively, each of which is mounted in anti-friction bearings 15 carrying cups 16 removably secured to the casing, and in the case of the wheel 2 the cup 16 is adjustably mounted along the median plane of the casing to permit of adjustment to compensate for wear on the surface of the bands. This attachment is secured by providing slots 17 in the extending ears 18 on the cups so that the entire cup may be shifted laterally and then fixed in any desired position by means of the bolts 19.

In Fig. 7 we have shown a modified means for adjusting the position of one of the two rolls, in which this means consists in forming in the casing an opening 35, in which is slidably mounted a bearing block 36, in which the shaft 37 of one of the two wheels is journaled in suitable ball bearings 38. The bearing block 36 is urged toward the other of the two wheels, shown in dotted line in the figure, by means of coil springs 39 interposed between the bearing block and a cap 40, the position of which may be adjusted by means of a screw 41 extending from the rear of the member, in which is formed the slot 35.

We have found that in order to impart to the abrasive substantially the full lineal speed of the wheels it is desirable to maintain the wheels in contact with each other under sufficient pressure to slightly distort or flatten the contacting portions 45 and 46 of the two wheels in the manner shown in Fig. 9. The material is then fed from the nozzle 18 into the entering throat opening between the wheels and is positively gripped and held by the yieldable surface elements on the wheels, and when discharged from the discharge throat opening 47 it has been given substantially the surface speed of the wheels.

It is also advisable to provide a discharge opening or nozzle in the pipe 10 of slightly shorter cross-sectional length than the width of the

wheels so that the abrasive is carried between the wheels and does not tend to slip over the edges of the wheels.

In many cases it may not be feasible to feed the abrasive to the wheel by gravity, and in this event we supply abrasive to the discharge nozzle 10 by feeding it into a conduit 50, through which a relatively small volume of low pressure air is passed by means of a blower. From this conduit the air and abrasive is discharged into a cylindrical chamber 51, from the bottom of which extends the pipe 52, which terminates in discharge nozzle 10. The top of the chamber 51 is open, but is closed by means of a fine screen 53, which allows excess air to escape, carrying with it any ultra fine material in the form of dust, while allowing the standard size particles of abrasive to pass downwardly through the pipe 52 and to the nozzle.

In Fig. 11 we have shown one type of wheel which may be employed, which consists of a wheel 60 on which is removably mounted a cylindrical band 63, which is fixed in position on the wheel by means of set screws 62. A yieldable band of rubber or similar material is attached 25 to the rim 61, and in this type of wheel it of course will be necessary to replace only the removable rim and band and not the entire wheel.

In Fig. 3 we have shown a modification of the wheels shown in Figs. 1 and 2, this modification employing wheels 21 and 22, each of which is provided around its periphery with a pneumatic tire or tube 23 of substantially rectangular cross-section so that the planes of contact between the two tires will be flat and will operate in substantially the same manner as the bands on the wheels in Fig. 1.

In Figs. 4 and 5 there is shown another modification of the bands employed, in which the yielding bands 24 are provided with a series of depressions or recesses 26 and this type of band may be used where it is desirable to project larger quantities of abrasive than can be readily passed between two flat connecting bands of the type shown in Figs. 1 and 2.

In Fig. 6 there is shown still another modification of the rotatable members or wheels in which a hard surfaced wheel 38 is employed in cooperation with a second wheel 31, the latter being provided with a yielding resilient encircling band 32.

It has already been explained that the finely divided abrasive material could be supplied to the rotating elements either by gravity or by other means. If the material is fed by gravity, a considerable head must be maintained on the material since we have found that there is a slight back pressure or movement of air in a direction opposite to that of the rotation of the wheels, which produces an air flow up the conduit 9. This counterflow is probably produced by the eddy currents formed around the surfaces of the rotatable elements at the discharge throat opening which produces a slight vacuum at the center of the discharge throat opening, causing the air to be drawn toward this point and to then flow upwardly past the wheels and into the upper portion of the casing, and to some extent of course upwardly through the supply pipe 9.

If other means are employed to supply the material, such as a blower to supply air and abrasive material to the conduit 5 as shown in Fig. 8, it is sufficient to maintain a relatively low pressure of incoming air sufficient to balance the back pressure in the conduit 52 of that figure.

The term "abrasive material" as employed 75

herein is intended to comprehend such material as sand, metallic grit and metallic particles of even fairly regular conformation, all of which may be employed for the purpose of cleaning, roughening or smoothing a surface against which the material is projected by the present apparatus.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In apparatus of the character described, the combination of two parallel rolls, one provided with a compressible surface, and said rolls being mounted with their surfaces substantially in contact, means adapted to drive one of said rolls, and means adapted to feed finely divided material to the entering throat opening between said rolls.

2. In apparatus of the character described, the combination of two parallel rolls mounted with their surfaces substantially in contact, and one of said rolls being adapted to yield slightly in the plane of the axes of said rolls to accommodate material passed between the same, and means adapted to feed finely divided material to the entering throat opening of said rolls along their line of surface contact.

3. In apparatus of the character described, the combination of two parallel rolls mounted with their surfaces substantially in contact, and one of said rolls having a compressible surface member, means adapted to drive one of said rolls, means adapted to feed finely divided material to the entering throat opening of said rolls.

4. In apparatus of the character described, the combination of two parallel rolls mounted with their surfaces closely adjacent to each other, an extensible band on one of said wheels adapted upon rotation of said wheel at a predetermined speed to extend and engage the other of said wheels in driving relation, means adapted to feed abrasive material to the entering throat opening of said rolls, and means adapted to rotate said roll provided with said band.

5. In apparatus of the character described, the combination of a casing, two rolls mounted therein in parallelism and having yielding bands encircling the same and in substantial contact, a conduit extending into said casing and terminating adjacent the entering throat opening of said rolls for feeding abrasive thereto and means adapted to drive one of said rolls.

6. In apparatus of the character described, the combination of a casing, a pair of rolls mounted in parallelism in said casing, yielding extensible bands secured to the peripheries of said rolls and with their surfaces in substantial contact, a conduit extending into said casing and terminating at a point close to the entering throat opening between said rolls for feeding abrasive thereto, said casing completely enclosing said rolls but having a discharge opening opposite the exit throat opening of said rolls, and means for driving one of said rolls.

7. In apparatus of the character described, the combination of a casing, a pair of rolls mounted in parallelism in said casing, yielding extensible bands secured to the peripheries of said rolls and with their surfaces in substantial contact, a conduit extending into said casing and termi-

nating at a point close to the entering throat opening between said rolls for feeding abrasive thereto, said casing completely enclosing said rolls but having a discharge opening opposite the exit throat opening of said rolls, and a flexible shaft connected to rotate one of said rolls.

8. In apparatus of the character described, the combination of a casing, a pair of rolls mounted in parallelism in said casing, yielding extensible bands secured to the peripheries of said rolls and with their surfaces in substantial contact, a conduit extending into said casing and terminating at a point close to the entering throat opening between said rolls for feeding abrasive thereto, said casing completely enclosing said rolls but having a discharge opening opposite the exit throat opening of said rolls, means for driving one of said rolls, and means for adjusting said rolls axially with respect to each other to compensate for wear on said bands.

9. In apparatus of the character described, the combination of two parallel rolls, each provided with a compressible surface, means for driving one of said rolls, means adapted to feed finely divided material to the entering throat opening between said rolls and means for maintaining pressure upon said two rolls urging them toward each other.

10. In apparatus of the character described, the combination of a frame, two parallel rolls mounted in said frame, each of said rolls being provided with a yieldable surface element secured thereto, means resiliently urging said rolls into contact, means for driving one of said rolls, and means adapted to feed finely divided material to the entering throat opening between said rolls.

11. In apparatus of the character described, the combination of a frame, two parallel rolls mounted therein, each of said rolls having a compressible surface element secured thereto and said rolls having said surface element in substantial contact, means for driving one of said rolls, and means for feeding finely divided material to the entering throat opening between said rolls at relatively slow speeds.

12. In apparatus of the character described, the combination of a frame, two parallel rolls mounted therein, each of said rolls having a compressible surface element secured thereto and said rolls having said surface element in substantial contact, means for driving one of said rolls, and means for blowing finely divided material at relatively slow speed and discharging the same to the entering throat between said rolls.

13. In apparatus of the character described, the combination of a frame, two parallel rolls mounted therein, said rolls having yieldable surface elements secured thereto and said surface elements being in substantial contact, means for supplying finely divided material uniformly across the major portion of the entering throat opening between said rolls, and means for driving one of said rolls.

14. In an apparatus of the character described, the combination of two parallel rolls having contacting surfaces of yieldable material, means for revolving said rolls at a velocity sufficient to urge said surfaces into increasing contact with each other, and means for feeding finely divided material between said rolls at their point of initial contact.

15. In an apparatus of the character described, the combination of movable members having opposed surfaces in contact over substantially their

entire width and providing an area of contact substantially as wide and long as said movable members are wide, means for moving said members in the same direction at their contacting portions, and means for introducing finely divided material between said surfaces at their point of initial contact.

5 16. In an apparatus of the character described, the combination of movable members having opposed surfaces in contact over substantially their

entire width and providing an area of contact substantially as wide and long as said movable members are wide, said members being composed of compressible material, means for moving said members in the same direction at their contacting portions, and means for introducing finely divided material between said surfaces at their point of initial contact.
